(Cl. D33—14)

FIG. 1

To all whom it may concern:

Be it known that I, Gordon L. Johnson, a citizen of the United States, residing at Olean, in the county of Cattaraugus and State of New York, have invented a new, original, and ornamental Design for a Drop Leaf Table, of which the following is a specification, reference being had to the accompanying drawing, forming part thereof, and in which

Fig. 1 is a perspective view of a drop leaf table, with the leaves extended, showing my new design; and

Fig. 2 is a perspective view thereof with the leaves in lowered position.

I claim:

The ornamental design for a drop leaf table, substantially as shown.
